UNITED STATES PATENT OFFICE.

FRANCIS GRANGER, OF GREENSBURG, PENNSYLVANIA.

SANITARY SCREEN.

1,203,868.

Specification of Letters Patent. Patented Nov. 7, 1916.

Application filed September 25, 1913. Serial No. 791,736.

To all whom it may concern:

Be it known that I, FRANCIS GRANGER, a citizen of the United States, and a resident of Greensburg, in the county of Westmoreland and State of Pennsylvania, have invented a new and useful Improvement in Sanitary Screens; and I do hereby declare the following to be a full, clear, and exact description thereof.

10 My invention relates to a screen for disseminating vapors of any desired character such as perfumes, disinfectants or antiseptics throughout a room or other apartment for the promotion of pleasing and sanitary or 15 hygienic surroundings and condition.

The invention has for its object the provision of a compact and convenient structure which may be readily hung for example adjacent heating apparatus or in any relation where the vapors may be most effectively and advantageously disseminated, by 20 an open window, before an electric fan.

A further object is to provide means whereby a change in the character or kind 25 of the vapors disseminated may be readily effected, or furthermore, where vapors of different kinds may be mingled and so disseminated.

With these objects in view the invention 30 consists in a construction and arrangement of parts one embodiment of which is illustrated in the accompanying drawing in which—

Figure 1 is a perspective view of the complete screen and of means for suspending the same; Fig. 2 is a vertical sectional view in a plane parallel with the face of the screen; Fig. 3 is a transverse vertical sectional view on the line 3—3 Fig. 1; Fig. 4 40 is a transverse horizontal sectional view on the line 4—4 Fig. 1; and Fig. 5 is a perspective view of one of the absorbent or screen members proper.

Referring to Fig. 1, the screen as a 45 whole comprises a frame-work 1, preferably of hollow metal construction, the bottom and opposite sides of which may be rigid or integral with each other while the top or cap member 2 may be made 50 preferably to fit over and inclose the ends of the side members as indicated in Figs. 2 and 3. The side members 3, 3, of the frame comprise vertical reservoirs 4, 4, and flanges 5, 5, which form slide or guide- 55 ways 6, 6, for the reception of the absorbent or wick screen members. For improving

the appearance of the screen as a whole and for protecting the absorbent or wick members the opposite sides of the screen frame may be filled in with protecting wire gauzes, 50 as 7, 7, thus forming an inclosed chamber 8 within the screen frame. The absorbing or wick screen members proper may consist of wire frames 9 of any suitable shape to conform to the shape of the frame and on these 65 wire frames may be stretched the strands 10 of the wick proper by winding the same from end to end as clearly indicated in Fig. 5, and bringing the opposite ends together as at 11, said ends being extended as at 12 70 to provide the necessary capillary connection with the fluid receiving reservoirs 4, 4. The extremities 12 of the wick member may be weighted as at 13 to facilitate entering the same within the reservoirs and at the 75 same time to insure that they extend well down into the volatile fluid.

In the use of the device the cap member 2 of the frame is removed and one or more of these wick frames 9 is inserted within 80 the guide channel 6 of the main frame, while at the same time the extremities 12 of the wick are inserted in the reservoirs at either side of the frame. In the construction here illustrated I have shown a main frame 85 adapted to receive two wick frames, but the number of frames may be increased as desired by properly modifying the construction of the main frame. In order that the cap 2 may not interfere with the capillary 90 transmission of the fluid throughout the wick said cap does not contact with the wick but is spaced slightly away therefrom as shown in Fig. 2.

By employing a main frame adapted for 95 the reception of several wick frames several useful results may be secured. In the first place the reservoirs 4, 4, on either side of the frame may contain volatile fluids of different characters, as for example one may contain oil of pine and the other a disinfectant, or one may contain a redolent or essential oil or fluid having the perfume of a certain flower, and the other a fluid having a different perfume. If it is desired to disseminate 100 the vapor from one of these fluids at a time the wick frame may be inserted with its wick terminal 12 extending into the reservoir 4 containing that fluid. If it is desired to change the character of the vapor disseminated it is only necessary to withdraw the wick frame and insert another with the wick 105 110

terminal of the latter extending into the opposite reservoir containing the fluid of different character. Therefore by a mere change of the wick screen or frame the character of the vapor as disseminated may be quickly changed. If, on the other hand, it is desired to combine two or more vapors, the wick terminal of one of the wick frames inserted in the main frame may extend into one of the reservoirs and that of the other into the other reservoir, said reservoirs containing different kinds of volatile fluid. If, furthermore, it is desired to produce an excessively pungent vapor of one kind the reservoirs on each side of the main frame may contain the same kind of fluid and the wick terminals of the two wick frames when inserted in the respective reservoirs will feed this fluid to both wicks.

With the one or several wick frames properly positioned within the main frame the screen may be suspended in a window of the room and the air as it enters the room will disseminate the vapors throughout the room.

On the other hand, the screen may be mounted in front of an electric fan and preferably on the safety guard of the fan itself. To this end I may provide a suitable form of supporting frame for the screen such as that illustrated in Fig. 1, wherein such frame comprises side members 14, 14, having the hooks 15 for embracing the side members 3 of the screen frame, a bottom member consisting of a supporting loop 16 adapted to embrace the bottom member of the screen frame. The side members may be extended as at 17, 17, to form fastening shanks of any desired construction which may be attached to the safety guard of the fan or secured to any other convenient part of the fan.

A screen of this character is peculiarly advantageous when used in hospitals or schools or in the sick room, for disseminating disinfecting vapors throughout the room, and furthermore it may also be employed for disseminating antiseptics, the delicate perfume of flowers or the pungent odor of the pine. In the latter case it is particularly valuable when used in sleeping rooms, as the

odor of the pine possesses well known soporific qualities. The device will also be found useful in theaters and public halls for disseminating purifying or disinfecting vapors.

It is to be understood that the screen may be made of various sizes to suit differing conditions, and may be constructed to contain one or a plurality of wick frames or screens as occasion may require.

Other changes and variations may be made in the structure and arrangement of the apparatus within the scope of the appended claims.

What I claim is:

1. In a vaporizer, the combination with a supporting frame having hollow side members forming fluid reservoirs, and having guide-ways, a wick frame having absorbent material stretched thereover, said frame being adapted to be placed in said guide-ways with a portion of said absorbent material extending into one of said reservoirs.

2. In a vaporizer, the combination with a supporting frame comprising side and bottom members, said side members being hollow to form fluid reservoirs and having guide-ways formed thereon, a wick frame adapted to fit within said guide-ways and carrying a wick member adapted to extend into one of said reservoirs and a cap member for said frame adapted to inclose said reservoirs and confine said wick frame within said main frame.

3. A vaporizer, comprising a supporting frame having hollow side members forming separate fluid reservoirs, a plurality of interchangeable separate wick frames carrying wicks the terminals of which are adapted to extend into said reservoirs, means for holding said wick frames in said supporting frame in operative connection with said reservoirs.

In testimony whereof, I the said FRANCIS GRANGER have hereunto set my hand.

FRANCIS GRANGER.
